UNITED STATES PATENT OFFICE.

CHARLES H. TRASK, OF LYNN, MASSACHUSETTS.

GEAR.

SPECIFICATION forming part of Letters Patent No. 436,324, dated September 9, 1890.

Original application filed December 9, 1889, Serial No. 333,164. Divided and this application filed February 24, 1890. Serial No. 341,416. (No model.)

To all whom it may concern:

Be it known that I, CHARLES H. TRASK, of Lynn, in the county of Essex and State of Massachusetts, a citizen of the United States, 5 have invented a new and useful Improvement in Gears, of which the following is a full, clear, and exact description, reference being had to the accompanying drawings, forming a part of this specification, in explaining its 10 nature.

The invention was originally described in my application for Letters Patent of the United States, filed December 9, 1889, Serial No. 333,164, and withdrawn therefrom by 15 amendment.

It relates to a gear having at the inner end of each tooth-receiving recess a slight projection or extension something in the form of a rib extending from side to side of the gear and 20 forming a narrow seat, against which the ends of the teeth of the meshing gear or pinion come in contact, the advantage of the seat being that it is narrow and prevents the grinding of the end of the entering tooth upon a 25 surface as large as the end of the tooth-receiving recess would present if the narrow seat were not employed.

In making the seat I use a gear-cutter which is the subject-matter of the application above 30 referred to.

In the drawings, Figure 1 is a view in plan of the gear-cutter for forming the seat. Fig. 2 is a view in vertical section thereof. Fig. 3 is a detail view representing parts of two intermeshing gears to illustrate the application of the invention. 35

A represents two meshing gear-wheels; a, their teeth; a', the teeth-receiving recesses, and a² a narrow seat at the inner end of each recess. These seats are formed integral with 40 the metal of the gear by means of the milling-tool B, having working-teeth b, of any suitable form, and also having in the face of each tooth the rounded or V-shaped recess b'. (See Fig. 2.) A tool having this recess will 45 form as the teeth of the gear are being milled a seating-rib at the base of each pocket or tooth-receiving recess.

Having thus fully described my invention, I claim and desire to secure by Letters Patent 50 of the United States—

As an improved article of manufacture, a gear having in each tooth pocket or recess a seating rib or bead a², as and for the purposes described.

CHARLES H. TRASK.
